UNITED STATES PATENT OFFICE.

LEONARD CHRONINGER AND JOHN E. ADAMS, OF FINDLAY, OHIO.

TROLLEY-WHEEL.

SPECIFICATION forming part of Letters Patent No. 715,983, dated December 16, 1902.

Application filed May 21, 1902. Serial No. 108,381. (No model.)

To all whom it may concern:

Be it known that we, LEONARD CHRONINGER and JOHN E. ADAMS, citizens of the United States, residing at Findlay, in the county of Hancock and State of Ohio, have invented 5 certain new and useful Improvements in Trolley-Wheels; and we do hereby declare the following to be a full, clear, and exact description of the invention, such as will enable others skilled in the art to which it appertains to make and use the same.

Our invention relates to certain new and useful improvements in trolley-wheels, and has for its object to produce a trolley-wheel 15 which will rapidly replace itself automatically when through accident it is caused to leave the trolley-wire.

Our invention further has for its object to mount such a trolley-wheel in its yoke so that 20 it may be readily removed and replaced by a new wheel when necessary.

Finally, this invention has for its object to render more secure the mounting for the trolley-wheel by dispensing entirely with screw- 25 threads and other frail parts.

In accomplishing these objects our invention consists in forming the trolley-wheel with conical ends having spiral grooves therein leading to the main groove in such a manner 30 that should the trolley-wire leave the main groove and fall into either of the spiral grooves the rotation of the trolley-wheel would lead the trolley-wire back into the main groove by means of the spiral groove.

The conical ends of the trolley-wheel are 35 made hollow, and the solid hub portion is located in the center. The trolley-yoke has an inwardly-extending projection on one arm and an open eye on the other arm. An axle-pin having a reduced end is passed through a 40 socket of the projection, with the trolley-wheel mounted on its reduced part, with its hub abutting against the end of the projection and a shoulder of the axle-pin.

With the above and other objects in view our invention further consists in the novel 45 details of construction and combinations of parts, to be fully described in the following specification and clearly set forth in the claims.

Referring to the accompanying drawings,

forming a part of this specification, and in which like characters of reference indicate same parts in the views, Figure 1 is a front 55 elevation of a trolley-wheel made in accordance with our invention, and Fig. 2 is a central longitudinal section thereof.

In the figures, 1 represents the yoke of the trolley, having an inwardly-extending projection 2 on one arm thereof and an open ring 60 or eye 3 on the other arm.

An axle-pin 4 fits in the eye 3 and has its reduced end seated in a socket 5, which extends part way through the projection 2. 65 Where the reduced portion of the axle-pin 4 begins there is an abrupt shoulder 6, between which and the end of projection 2 trolley-wheel 7 is mounted to rotate on the said reduced portion of axle-pin 4.

The trolley-wheel 7 is composed of a central solid hub 8, which loosely fits against shoulder 6 at one end and against the end of projection 2 at the other end and the two conical hollow shells 9 at the ends, the deep 75 groove 10 being centrally located on the surface and the spiral grooves 11 leading thereto from the ends of the conical shells 9.

The axle-pin 4 is retained in its position by a pin 12, passing through perforations in said 80 axle-pin and the sides of eye 3.

From the foregoing it will be seen that with a trolley-wheel of this description the wire may be more easily found by the operator, for even if it does not fall within the main 85 groove 10 it is a simple matter to cause it to strike one of the spiral grooves, by means of which it will be led to the main groove. When it is desired to remove a trolley-wheel of this type, the pin 12 is removed and the 90 axle-pin 4 withdrawn through the eye 3, when the wheel is free to be drawn off of projection 2.

Having fully described our invention in detail, what we claim as new, and desire to secure 95 by Letters Patent, is—

1. A trolley comprising a yoke, a projection on one arm thereof, an axle-pin passed through an eye in the other arm of the yoke and having a reduced portion fitting in a socket of the projection, and a wheel mounted on the reduced portion of the axle-pin.

2. A trolley comprising a yoke, an inwardly-extending projection on one arm thereof, an

5 axle-pin fitting within an eye in the other arm of the yoke and provided with a reduced portion seated in a socket in said projection, a shoulder on the axle-pin, and a trolley-wheel mounted on the reduced portion of the axle-pin between the shoulder and the end of said projection.

3. A trolley comprising a yoke, an inwardly-extending projection on one arm thereof, an 10 axle-pin fitting within an eye in the other arm of the yoke and provided with a reduced portion seated in a socket in said projection, a shoulder on the axle-pin, and a trolley-wheel mounted on the reduced portion of the axle-

pin between the shoulder and the end of said 15 projection, said trolley-wheel being formed of a central solid hub with hollow conical shells on its ends and having a central main groove with spiral grooves leading thereto from the ends of the conical shells.

In testimony whereof we affix our signatures in presence of two witnesses.

LEONARD CHRONINGER.
JOHN E. ADAMS.
